SPRING COILING MACHINE

Joseph Gogan, Lakewood, Ohio

Application February 23, 1934, Serial No. 712,599

10 Claims. (Cl. 153—67)

The present invention relates to machines for making springs, and more particularly production machines for making relatively heavy coil springs of the helical type, such as those now being employed in automobile suspensions.

An object of the invention is the provision of a novel coiling machine which will be rugged and simple in construction, inexpensive to manufacture, and semi-automatic in operation.

10 Another object of the invention is the provision of a novel machine for making coil springs, particularly adapted to high production purposes, wherein a predetermined length of rod stock is coiled about a mandrel with the free ends thereof lying close to the adjacent convolutions.

Another object of the invention is the provision of a novel machine for making coil springs from hot rod stock, by coiling the stock about 20 a mandrel while the free end thereof is advanced longitudinally of the mandrel, and subsequently stripping the finished spring from the mandrel.

Further objects and advantages of the invention will be apparent to those skilled in the art 25 to which it pertains from the following description of the preferred embodiment thereof, described with reference to the accompanying drawings, in which

Fig. 1 is a front perspective of a coil spring machine embodying the present invention;

Fig. 2 is a longitudinal section through the center of the machine on the line 2—2 of Fig. 3, with portions shown in elevation.

Fig. 3 is a section on the line 3—3 of Figs. 2 35 and 4, with portions shown in elevation;

Fig. 4 is a top plan view of the mechanism shown in Fig. 3;

Fig. 5 is a longitudinal section through the feed screw on the line 5—5 of Fig. 3;

Fig. 6 is an enlarged section of the chuck shown in Fig. 2;

Fig. 7 is an enlarged view of a portion of Fig. 1;

Fig. 8 is a section on the line 8—8 of Fig. 7;

Fig. 9 is a perspective view of the finished 45 spring;

Fig. 10 is a wiring diagram of the electrical circuits of the machine;

Fig. 11 is a longitudinal section through the limit switch shown in Fig. 1, and

50 Fig. 12 is a section on the line 12—12 of Fig. 11.

Similar reference characters designate corresponding parts through the several views of the drawings.

The preferred embodiment of the invention 55 illustrated and described herein is a machine for

making relatively heavy coil springs, such as those used in the front suspension of automobiles, from a predetermined length of hot rod stock. It is to be understood that such variations in the construction of the machine hereinafter described, as come within the knowledge of those skilled in the art, are within the scope of this invention, and that the machine shown is merely illustrative thereof.

Referring to Fig. 1, the frame of the machine 10 illustrated is designated in general by the reference character A, and comprises a bed 10, supported on legs 11, 12 and 13, and an overhead member 14 supported on the bed 10 by brackets 15 and 16. The work W in the form of a predetermined length of hot rod stock, both ends of which are tapered as illustrated, is placed in the machine by an operative from the front, underneath a lead screw 20, with the front end of the rod resting upon a mandrel 21 underneath a 20 clamping bar 22 of a chuck designated in general by the reference character C. The clamp bar 22 is then actuated to clamp the end of the work W to the mandrel. The chuck C is carried by and forms part of a spindle designated in general by the reference character B, and after the end of the work is clamped to the mandrel, the spindle B, including the mandrel 21, is rotated by mechanism hereinafter referred to, to coil the work or rod stock about the mandrel. During the 30 coiling operation the free end of the work or rod is prevented from rotating with the spindle and fed longitudinally of the mandrel by the lead screw 20, rotated at a speed proportional to the speed of the spindle. After the free end of the 35 work or rod stock leaves the lead screw 20 it is rolled down against the mandrel 21 by a roller 24, after which the mandrel 21 is withdrawn and the spring allowed to drop through the bottom of the machine.

The spindle B comprises a spindle shaft 26, driven from an electric motor 27, through a gear reduction designated in general at 28, and the spur gears 29 and 30. The spur gear 30 is operatively connected to the spindle shaft 26 by a friction or slip clutch E, to prevent injury to the motor in the event that the machine becomes jammed, etc. The friction clutch E is of conventional construction and comprises an annular flange 31 on the gear 30 engaged between the plates 32 and 33 connected to the spindle shaft 26. Plate 32 is held in engagement with the other plate 33 by compression springs 34, the pressure of which may be adjusted to change the load at which the clutch will slip. The spindle shaft 26

is rotatably supported in brackets 38 and 39, bolted or otherwise secured to the bed 10. A hand wheel 41 fixed to the spindle shaft 26 is provided for the purpose of manually turning over the spindle.

The chuck C comprises a body portion 42, secured to the spindle shaft 26 by means of bolts 43, and is preferably keyed to the shaft to prevent any rotation between the parts. The clamp bar 22 pivotally supported in the body portion 42 by a pin 44 carries a lever 45 pivotally connected to the rear end thereof and provided with a roller 46 at the lower or free end adapted to roll on a surface 47 formed on the body portion 42. The lower end of the lever 45 is cylindrical and fits in a rectangular opening 49 in the enlarged end 50 of a rod 51 slidably supported in a longitudinal aperture in the spindle shaft 26. Longitudinal reciprocation of the rod 51 moves the roller 46 over the surface 47 and causes the clamping bar 22 to engage or disengage the work, depending upon the direction of reciprocation.

The rod 51 is reciprocated longitudinally to cause the clamp bar 22 to engage and disengage the work by a bar 55, projecting through an aperture in the rod 51 and an elongated slot 56 in the spindle shaft 26. The bar 55 is connected to lugs 57 formed integral with an annular member 58, by pins 59. The annular member 58 is rotatably supported on the spindle shaft 26, and is reciprocated longitudinally thereof by a second annular member 60 supported coaxial therewith. The annular member 58 is adapted to be rotated within the second annular member 60, and the two members are held in assembled relationship by a disk 62 bolted to the annular member 58. Anti-friction thrust bearings 63 are interposed between the members 58 and 60.

The member 60 is provided on opposite sides thereof with projections 65 provided with rollers 66 which engage in slots 67 formed in the upper ends of levers 68. The levers 68 are fixed to a horizontal shaft 70 rotatably supported in bosses 71 secured to the bed 10. A lever 72 fixed to the shaft 70 midway between the lever 68 is operatively connected to the piston rod 74 of a fluid pressure operated motor designated, in general, by the reference character H, by a link 75. The fluid pressure actuated motor H comprises a cylinder 76 secured to a bracket 77 carried by the bed 10, and a cylinder head 78. A piston 80 slidably supported in the cylinder 76 and connected to the piston rod 74 by a nut 81 is adapted to be reciprocated towards the right, as viewed in Fig. 7, by fluid pressure, preferably air, admitted to the cylinder at the left of the piston through a port 83. The piston 80 is continuously urged toward the left, as viewed in the above mentioned figure, by a compression spring 84 sur-

rounding the piston rod 74 and compressed between the piston 80 and the lower end of an aperture 85 formed in the bracket 77. The supply of fluid pressure to the cylinder 76 is controlled by a foot operated valve 86, which connects a pipe 87 communicating with the port 83 and the valve 86 with fluid pressure when the pedal 88 is released, and with exhaust or atmosphere when the pedal is depressed. The fluid pressure supply line is designated by the reference character 89. The valve 86 is of conventional construction and a detailed description thereof is considered unnecessary to the full understanding of the present invention.

The mandrel 21 is secured to a member 90 rotatably supported in a bracket 91 slidably sup-

ported on suitable ways 92, formed on the overhead member 14. Suitable bushings and an anti-friction thrust bearing 93 are interposed between the member 90 and the bracket 91. The mandrel 21 is provided with a squared end 94 adapted to project through a rectangular aperture in a face plate 95 of the chuck C. The plate 95 is secured to the body portion 42 of the chuck by bolts 96 and the mandrel 21 is driven from the spindle shaft 26 through the chuck. The mandrel 21 is also provided with a longitudinal passage 97 through which air is blown for the purpose of cooling the mandrel. The air connection is made by means of a pipe 98.

The bracket 91 is reciprocated on the ways 92 to 15 engage and disengage the squared end 94 of the mandrel 21 with the chuck C, by a double acting fluid pressure actuated motor designated in general by the reference character J. The motor comprises a double acting piston 100 attached 20 to a piston rod 101 and slidably supported within a cylinder 102 fixed to the overhead member 14 by brackets 103 and 104. The piston rod 101 is secured to a plate 105 attached to the bracket 91 by screws 106. The left hand end of the cylinder 102 is provided with cushion means for limiting the movement of the piston, etc., towards the left, as viewed in Fig. 2, and taking the impact thereof. The cushion means referred to comprises a member 110, positioned in the cylinder 30 102 adjacent the cylinder head 111, and provided with a counterbore 112 within which a compression spring 113 is positioned. The spring 113 engages a disk-shaped member 114 slidably supported in the cylinder 102 which, in turn, engages a cup-shaped member 115 adapted to engage the piston 100 when the same is at or near the left hand end of its stroke. The movement of the disk-shaped member 114 and the cup-shaped member 115 towards the right is limited 40 by a rod 116, secured to the cylinder head 111, provided with an enlarged head 117 positioned within the cup-shaped member 115. The rod 116 extends through the center of the members 114 and 115 which are free to slide thereon. 45

The supply of fluid pressure, preferably air, to the motor J is controlled by a foot actuated valve 120. A pipe 121 communicates with the valve 120 and the left hand end of the cylinder 102, and a pipe 123 communicates with the valve 120 50 and a port 124 in the right hand end of the cylinder 102. When the foot pedal 125 of the valve 120 is depressed, the pipe 121 is connected to the fluid pressure supply line 89, and the pipe 123 opened to exhaust, with the result that the bracket 91 etc., is moved to the right. When the foot pedal 125 is released the direction of the flow of fluid in the pipes 121 and 123 is reversed, moving the bracket 91 etc. to the left.

As was previously stated, a feed screw 20 prevents the free end of the work W from rotating with the spindle B and feeds the same longitudinally of the mandrel 21. The feed screw 20 is provided with a helical groove 125 in the nature of a thread within which the work W is held, 65 and is driven at a predetermined speed in a direction opposite to that of the spindle B through gears 126 and 127, the former of which is fixed to the body portion 42 of the chuck C and the latter to a stud shaft 128 rotatably supported in 70 a bracket 129. The left hand end of the feed screw, see Fig. 5, is secured to a disk 130 by means of a bolt 131, and the disk 130 is detachably secured to a disk 135 fixed to the shaft 128, by screws 136. The disks 130 and 135 have a 75

tongue and groove connection which prevents any relative rotation between the same.

The right hand end of the feed screw 20 is slidably keyed to an annular member 140 detachably connected to an annular member 141, by means of screws 142, fixed to the end of a stud shaft 143 rotatably supported on a bracket 144. Sufficient clearance is provided between the right hand end of the feed screw 20 and the annular member 141 to permit removal of the feed screw and the members 130 and 140 as a unit when the screws 136 and 142 have been removed without disturbing the bearings or brackets 129 and 144. The foregoing construction permits quick replacement of the feed screw when desired. The brackets 129 and 144 are secured by means of bolts 145 to the brackets 39 and 16, respectively, and the construction is such that the feed screw 20 can be adjusted circumferentially about the axis of the spindle B, a plurality of bolt holes 146 being provided for this purpose, see Fig. 3.

The roller 24 which rolls the end of the work W against the mandrel after it leaves the feed screw 20 is rotatably supported on a pin 150 fixed in a forked lever 151, and is provided with an annular flange 152 which rolls or presses the tapered end of the work W into engagement with or towards the adjacent convolution. The lever 151 is pivotally supported on a pin 155 fixed in a bracket 156 clamped to a rectangular bar 157 by bolts 158. The bar 157 is supported by brackets 160 fixed to the brackets 39 and 16 by bolts 161.

The rear end 165 of the lever 151 is circular in shape and engages a recess in a bearing member 166 supported in a counterbore formed in a member 167. The member 167 is in the nature of a piston and is slidably keyed within a cylindrical or cup-shaped member 168 clamped to the bar 157 by the bolts 158. The end 165 of the lever 151 is continuously held in contact with the bearing member 166 by a spring member 170 supported by studs 171 fixed to the member 167 and extending over a pin 172 secured in the end 165 of the lever 151.

The piston member 167 is continuously urged in an upward direction by a compression spring 173 compressed between the member 167 and a disk 174 supported on the upper end of a tubular member 175 threaded into the bottom of the member 168. The compression of the spring 173 can be adjusted by rotating the tubular member 175, and the member 175 locked in any adjusted position by a screw 176. The upward movement of the piston member 167, and, in turn, the downward movement of the roller 24, is limited by a bolt 179 extending through the center of the member 167, the head 180 of which overlies a portion of the member 167 underneath the bearing member 166. The lower end of the bolt 179 projects through the tubular member 175 and carries a nut 181 threaded onto the lower end thereof by means of which the upper limit of the member 167 can be adjusted. The roller assembly just described and which is designated generally by the reference character D is adjustable along the bar 157 to accommodate different lengths of springs. The compression of the spring 173 is adjusted by means of the tubular member 175 to take care of stock of different thickness, and the distance of the roller 24 from the axis of the spindle B is adjusted by the nut 181 to accommodate both mandrels of different diameters and different size stock.

The motor 27 is a reversible three phase alter-

nating current motor, provided with an electrically controlled brake 185 applied to one end of the armature shaft. The control box 186, see Fig. 1, houses the solenoid operated control switch for the motor 27, designated in general by the reference character K, see Fig. 10. The operating solenoid is indicated at 187, and is in series with the foot operated push button 188, the operating pedal 189 of which extends underneath the foot pedal 88 and is operated simultaneously therewith. The power lines are indicated by the reference characters 41, 42 and 43 and the motor terminal connection by the reference characters T¹, T² and T³. Fuses are indicated at 190 and 191. The solenoid 192, which controls the operation of the brake 185, is also in series with the push button 188. The construction is such that the brake is released when the pedal 88 is depressed.

A limit switch, designated in general by the reference character M, is provided for always bringing the spindle B to rest at a predetermined point in the rotation thereof. The limit switch M comprises a frame 195 supported by a member 196 attached to the bracket 38, see Fig. 1, and a shaft 197 rotatably supported in the frame 195 by anti-friction bearings 198. The shaft 197 is connected to the spindle shaft 26 by a coupling 200 and is rotated therewith. A plurality of insulator disks or commutators 201, adjustably connected to the shaft 197, carry contact segments 202 on the circumference thereof embracing about 95% of the circumference. The segments 202 are connected in series by a lead 203 and contact is made with the segments by spring pressed brushes 204 slidably supported in insulating brush holders 205. The brushes 204 etc. are connected in shunt circuit with the push button 188 by the leads 207 and 208 and maintain the circuit to the operating solenoids 187 and 192, after the pedal 88 is released until a predetermined point in the rotation of the spindle B, thus always stopping the spindle in a predetermined position. The disks or commutators 201 are adjustable on the shaft 197 for the purpose of permitting the spindle to be stopped at different positions as desired. A manually operated switch 210 in series with the commutator switch, permits the machine to be placed under the sole control of the push button 188.

It is believed that the operation of the machine will be apparent from the foregoing description thereof, suffice it to say that with the machine at rest and the parts in the position shown in Fig. 7, the work, in the form of a predetermined length of rod stock tapered off at both ends, is inserted underneath the feed screw 20 until the end thereof rests underneath the clamp bar 22, with the flat face adjacent the face plate 95 of the clutch, after which the foot pedal 88 is depressed to clamp the end of the work between the clamp bar 22 and the mandrel 21. When the foot pedal 88 is depressed the pedal 189 is depressed simultaneously therewith, closing the switch 188, energizing the solenoids 187 and 192, which start the motor 27 and release the brake 185.

As the wire is coiled about the mandrel 21 the same is fed lengthwise thereof by the feed screw 20. As the end of the coil is approached the work engages underneath the roller 24 which rolls the free end of the work against the mandrel and presses the last convolution against the convolution adjacent thereto, thus gauging the length of the spring. When the coil has been completely formed on the mandrel the foot pedals 75

88 and 86 are released and the spindle B comes to stop at a predetermined point in the present illustration with the clamp bar 22 on top. The foot pedal 125 is then depressed, with the result that the slide 91 and the mandrel 21 are moved to the right, as viewed in Fig. 1, stripping the spring from the mandrel and allowing it to drop through the bottom of the machine. When the foot pedal 125 is released the slide 91 and mandrel 21 are returned to their initial position and the machine is ready for the next operation.

The machine shown is set up for making right hand springs, but is capable of making left hand springs by merely reversing the direction of rotation of the motor 27, dropping the feed screw 20 until the top thereof is approximately even with the bottom of the mandrel 21, and adjusting the limit switch M so that the spindle will stop with the clamp bar 22 underneath the mandrel. When operating the machine to make left hand springs, set up as outlined above, the work is inserted in the machine above the feed screw 20 and underneath the mandrel 21.

From the foregoing it will be apparent that applicant has produced a new and improved machine for making springs, etc. While the preferred embodiment of the invention has been illustrated and described, I do not wish to be limited to the construction shown, which may be varied within the scope of the invention, and I particularly point out and claim as my invention the following:

1. In a machine of the character described, the combination of a frame, a mandrel adapted to have rod stock coiled thereabout to form a helical coil rotatably supported by said frame, means for clamping one end of the rod stock into engagement with said mandrel, means for rotating said mandrel, means for engaging the rod stock projecting from said mandrel and limiting the rotation thereof, means for feeding the rod stock longitudinally of the mandrel, and fluid pressure actuated means for stripping the helical coil from said mandrel.

2. In a machine of the character described, the combination of a frame, a spindle comprising a mandrel adapted to have rod stock coiled thereabout, a chuck carried by said spindle, said chuck comprising a clamp bar pivotally supported therein for clamping the rod stock in engagement with said mandrel, means for moving said clamp bar towards and from said mandrel, means for rotating said spindle, a feed screw rotatably supported by said frame for preventing the rod stock not in engagement with said spindle from rotating therewith and for feeding the rod stock longitudinally of said mandrel, means for rotating said feed screw, a roller supported by said frame and adjustable longitudinally of said mandrel for rolling the end of the rod stock into contact with said mandrel after it has disengaged said feed screw.

3. In a machine of the character described, the combination of a frame, a spindle rotatably supported by said frame, a mandrel rotatably supported by said frame coaxial with said spindle, means for rotating said spindle, means for operatively connecting said mandrel to said spindle, fluid pressure actuated means for reciprocating said mandrel to and from said spindle to engage and disengage the same therewith, means supported by said spindle for clamping rod stock in engagement with said mandrel, means for engaging the rod stock not in contact with said mandrel and limiting the rotation thereof with

said mandrel, and means for feeding the rod stock longitudinally of said mandrel to form a helical coil.

4. In a machine of the character described, the combination of a frame, a spindle rotatably supported by said frame, a mandrel rotatably supported by said frame coaxial with said spindle, means for rotating said spindle, means for operatively connecting said mandrel to said spindle, means for reciprocating said mandrel to and from said spindle to engage and disengage the same therewith, means supported by said spindle for clamping rod stock in engagement with said mandrel, means for engaging the rod stock not in contact with said mandrel and limiting the rotation thereof with said mandrel, means for feeding the rod stock longitudinally of said mandrel to form a helical coil, and means for rolling the end of the rod stock against said mandrel and stripping the coil therefrom upon reciprocation of said mandrel in a direction away from said spindle.

5. In a machine of the character described, the combination of a spindle comprising a mandrel adapted to have rod stock coiled thereabout, means carried by said spindle for holding one end of the rod stock, an electric motor for rotating said spindle, means for preventing rotation of the rod stock not engaged by the spindle about the axis thereof, means for feeding the rod stock longitudinally of the mandrel, and control means for said motor operatively connected to said spindle for opening the circuit to said motor whereby said spindle is stopped in a predetermined position.

6. In a machine of the character described the combination of a frame, a spindle rotatably supported by said frame, a mandrel rotatably supported by said frame coaxial with said spindle, means for rotating said spindle, means for stopping said spindle in a predetermined position, means for operatively connecting said mandrel to said spindle, means for reciprocating said mandrel to and from said spindle to engage and disengage the same therewith, means supported by said spindle for clamping rod stock in engagement with said mandrel, means for engaging the rod stock not in contact with said mandrel and limiting the rotation thereof with said mandrel, means for feeding the rod stock longitudinally of said mandrel as it is coiled thereabout to form a helical coil, and common means for rolling the end of the rod stock against said mandrel and stripping the coil from said mandrel upon reciprocation thereof in a direction away from said spindle.

7. In a machine of the character described the combination of a frame, a spindle rotatably supported by said frame, a member slidably supported by said frame, a mandrel rotatably supported by said member coaxial with said spindle, means for rotating said spindle, means for operatively connecting said mandrel to said spindle, means fluid pressure actuated for reciprocating said member for moving said mandrel to and from said spindle to engage and disengage the same therewith, means supported by said spindle for clamping rod stock in engagement with said mandrel, and means for feeding the rod stock longitudinally of said mandrel to form a helical coil.

8. In a machine of the character described the combination of a frame, a spindle rotatably supported by said frame, an electric motor for rotating said spindle, means for operatively connect-

- ing said spindle and said motor, a limit switch operatively connected to said spindle for controlling the circuit to said motor whereby said spindle is stopped in a predetermined position, a bracket slidably supported by said frame, a mandrel rotatably supported in said bracket coaxial with said spindle about which rod stock is adapted to be coiled to form a spring, means for operatively connecting said spindle with said 5 mandrel whereby said mandrel is rotated therewith, means for reciprocating said bracket towards and from said spindle to engage and disengage said mandrel with said spindle, means for clamping rod stock adjacent said mandrel, and 10 means for limiting the rotation of the rod stock not in engagement with said mandrel from rotating therewith.
9. In a machine of the character described the combination of a frame, a spindle rotatably supported by said frame, an electric motor for rotating said spindle, a gear reduction for operatively connecting said motor with said spindle, a manually controlled switch for closing the circuit to said motor, control means for said motor operatively connected to said spindle for interrupting the circuit to said motor after the opening of 15 said manually controlled switch and stopping said spindle in a predetermined position, a member slidably supported by said frame, a mandrel rotatably supported by said member coaxial with said spindle, means for detachably connecting said mandrel with said spindle whereby said mandrel is rotated with said spindle, a fluid pressure operated means for moving said member relative 20 to said frame to engage and disengage said mandrel with said spindle, a chuck supported by said spindle adjacent said mandrel, a clamp bar supported by said chuck for clamping one end of rod 25 stock in contact with said mandrel, fluid pressure actuated means for controlling the actuation of said clamp bar, means for connecting said clamp bar with said fluid pressure actuated means, a feed screw rotatably supported by said frame adjacent said mandrel for preventing the free end of the rod stock from rotating with said mandrel and for feeding the rod stock longitudinally thereof, means for adjusting said feed screw circumferentially of the axis of said spindle, means 30 for rotating said feed screw for said spindle, a roller member rotatably supported adjacent said mandrel for rolling the free end of the rod stock into contact with said mandrel, yieldable means for continuously urging said roller member towards said mandrel, an adjustable stop for limiting the movement of said roller member towards said mandrel, and means for adjusting said roller longitudinally of the axis of said mandrel.
10. In a machine of the character described 35 the combination of a frame, a spindle rotatably supported by said frame, a mandrel rotatably supported by said frame, means for rotating said mandrel, means for operatively connecting said mandrel to said spindle, fluid pressure actuated 40 means for moving said mandrel towards and from said spindle to engage and disengage the same therewith, means supported by said spindle for clamping rod stock in engagement with said mandrel, means for engaging the rod stock not in 45 contact with said mandrel and limiting the rotation thereof, means for feeding the rod stock longitudinally of said mandrel as it is coiled thereabout, means for rolling the end of the rod stock against said mandrel, and means for stripping the 50 rod stock from said mandrel upon movement of the mandrel away from said spindle.

JOSEPH GOGAN.
